WITNESS:

UNITED STATES PATENT OFFICE.

HENRY WATERSTONE, OF MONTGOMERY, WEST VIRGINIA.

FUEL-FEED SYSTEM.

Application filed December 16, 1922. Serial No. 607,428.

To all whom it may concern:

Be it known that I, HENRY WATERSTONE, a citizen of the United States, residing at Montgomery, in the county of Fayette and State of West Virginia, have invented new and useful Improvements in Fuel-Feed Systems, of which the following is a specification.

This invention relates to a vacuum tank for internal combustion motors, the general object of the invention being to provide a float controlled valve for controlling the suction line from the carburetor to the said tank.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a view showing the invention in use.

Figure 2 is a longitudinal sectional view through the tank.

Figure 3 is a section on line 3—3 of Figure 2.

Figures 4 and 5 are detail views.

In these views 1 indicates a tank which has its lower end closed and its upper end provided with a cover 2 which is bolted to a flange 3 at the top of the tank. A partition 4 divides the tank into upper and lower chambers and said partition is provided with an L-shaped discharge spout 5 which is controlled by a flap valve 6. The bottom of the tank is provided with a drain cock 7 and the pipe 8 connects the lower part of the tank with the carburetor. A pipe 9 passes through the cover 2 and this pipe is adapted to be connected with the supply tank in any desired manner. A pipe 10 is also carried by the cover and this pipe is connected by the tube 11 with the carburetor of the motor, as shown, so that the suction created by the moving pistons will form a vacuum in the upper chamber of the tank, this vacuum causing the valve 6 to close and thus shut off the lower chamber from the upper chamber so that fuel

into the upper chamber through the pipe 9. A valve 12 normally closes the lower end of pipe 10 through means of the spring 13 which engages one end of the lever 14 which carries the valve 12 at its other end and which is pivoted to a frame 15, as shown at 16. This frame is connected with the cover 2. A bell crank lever 16' is also pivotally secured to the frame 15 and one part of this bell crank lever is adapted to engage the lever 14 so as to move the same against the action of the spring 13 and open the valve 12. This bell crank lever 16' is actuated by the lowering of the float 17 in the upper chamber which engages a projection 18 on the rod 19 so as to move the rod 19 downwardly and thus move the bell crank lever 16' as said rod is fastened to said lever. A projection 20 on the rod is engaged by the float in its upward movement. A tube 21 is connected with the upper end of the bottom chamber so as to prevent a vacuum being formed therein when the liquid is being discharged therefrom.

From the above it will be seen that when the motor is in operation and there is no fuel in the upper chamber, the float will cause the bell crank lever 16' to open the valve 12, thus permitting a vacuum to be formed in the upper chamber thus drawing fuel thereinto from the main tank. When the fuel in the upper chamber reaches a certain level the float will engage the projection 20 and thus raise the arm 16', and permit the valve 12 to close. As soon as this takes place the valve 6 will open under the weight of the fuel so that the fuel in the upper chamber will flow into the lower chamber and will then pass to the carburetor through the pipe 8. As soon as the level of fuel in the upper chamber reaches a point where the float will again engage the projection 18 the valve will open to permit a vacuum to take place in the upper chamber and thus the operation will be repeated.

The tube 11 is connected with the carburetor adjacent the flange thereof and just ahead of the butterfly valve. This arrangement of parts will prevent a vacuum being created in the carburetor. A small hole 22 is formed in the lid of the vacuum tank.

It is thought from the foregoing description that the advantages and novel features of my invention will be readily apparent.

I desire it to be understood that I may make changes in the construction and in the

combination and arrangement of the several parts, provided that such changes fall within the scope of the appended claim.

What I claim is:—

- 5 In a vacuum tank, a yoke-shaped frame connected with the cover thereof and having an opening in one limb thereof, a lever pivoted in said opening, a valve at one end of said lever, a spring engaging the other
- 10 end of the lever and the cover for holding

the valve closed, a bell crank pivoted on the frame and engaging the lever adjacent its spring end, a rod connected with the bell crank lever and having projections thereon and a float on the rod for engaging the 15 projections.

In testimony whereof I affix my signature.

HENRY WATERSTONE.
